(57) **CLAIM**

The ornamental design for a mirrored case, as shown and described.

DESCRIPTION

FIG. 1 is front perspective view of a mirrored case showing our new design;

FIG. 2 is a front view thereof, the rear view being identical; FIG. 3 is a top plan view of the mirrored case shown in FIG. 1;

FIG. 4 is a bottom plan view thereof;

FIG. 5 is a left side elevational view thereof, the right side elevational view being identical; and,

FIG. 6 is a perspective view of the mirrored case shown in FIG. 1 with the case in an open position.
